UNITED STATES PATENT OFFICE

BENNO FREDERICK JANCKE, OF NEW YORK, N. Y., ASSIGNOR TO SHELTON-JANCKE CORPORATION, OF NEW YORK, N. Y., A CORPORATION OF NEW JERSEY

APPARATUS FOR USE IN WAVING HAIR

Application filed November 15, 1928, Serial No. 674,888. Renewed May 26, 1928.

This invention relates to an apparatus or device for use in the art of waving hair, that is, for producing the so-called "permanent wave" in hair, and aims to provide improvements therein.

The invention provides a device whereby the requisite heat which is used in the waving of hair may be applied in such manner that discomfort from excessive heat around 10 the head during the treatment, burning and injury to the hair from such heat, and burning of the hands of attendants in handling the heaters now in use, may be avoided.

The energy for producing the heat is transmitted without the use of wires from an electric circuit to the heat-generating element in which heat is directly developed, so that such wires and other parts as may constitute a part of the device which is handled, and which 20 comes in immediate proximity to the person whose hair is being treated, need not be externally heated to temperatures which are objectionable to the attendants or to the person undergoing treatment. Moreover, the heat-generating element may be placed or located 25 in positions most advantageous for the development of its heat and for conveying heat to the liquids and other material used in the process of waving, and to the hair itself.

30 Several embodiments of the invention are illustrated in the accompanying drawings.

Referring to said drawings.

Figures 1 to 3, inclusive, illustrate a form of the device readily adaptable for connection to an ordinary lighting circuit, and usable with direct or alternating current without alteration.

Fig. 4 is the wiring diagram of the embodiment shown in Figs. 1 to 3.

40 Fig. 5 is an alternative wiring diagram.

Figs. 6 and 7 are diagrams of other circuits which may be employed, and which are adaptable for connection to wire systems supplied with alternating current.

45 Fig. 8 illustrates still another embodiment

of the invention in which the energy for heating is transmitted by a directional wireless transmitter such as used in wireless telephony or telegraphy.

Fig. 9 illustrates still another embodiment 50 in which the energy is transmitted through space from a single coil (of the pancake type).

Fig. 10 is a cross-section through the pancake winding.

55 Figs. 11, 12, 13 and 14 illustrate other embodiments of the part of the apparatus shown in Fig. 3.

Figs. 15, 16 and 17 illustrate three forms 60 of the pin or rod on which the hair is wound for treatment.

Fig. 18 is a view showing the apparatus applied to a strand of hair in process of permanently waving it.

65 Apparatus for permanent waving are commonly made with a plurality or multiplicity of heating units (often twenty or more) for heating numerous individual strands or curls of hair. A single unit will be first described.

Referring to said drawings, numeral 10 70 designates a heat-generating element which may have a great variety of forms, as will be hereinafter more fully explained, and 15 designates any suitable means for transmitting by induction, energy for producing heat in said element 10. These means 15 comprise a coil 16 connected in the circuit of an alternating or oscillating current, as shown in the diagrams Figs. 4, 5, 6 and 7.

75 The transmitting means 15 may also have 80 a variety of forms, some of which are illustrated and described herein.

The heat-generating means 10 is a piece 85 or pieces of metal, preferably magnetic iron or steel, for example, adapted to be placed in proximity to the hair undergoing treatment, and in which heat is developed through the action of the varying flux transmitted through space from said transmitting means 90

As shown in Fig. 15, the heat-generating element 10 may comprise a pin in the form of a metal tube 20 around which the hair to be treated is wound, and a wire bail or loop 21, pivoted to one end of the tube 20, as indicated at 22, and adapted to frictionally engage the other end, as indicated at 23, the bail or loop 21, when in place, serving to hold the wound hair on the tube 20 from un-

10 winding.

As shown in Fig. 16, the heat-generating element 10 may comprise an iron rod 25, preferably having aluminum tips 26, 27, at its ends, and surrounded by a porous jacket 28

15 of suitable material, as, for example, unglazed porcelain. The porcelain serves for absorbing liquid which is vaporized in the process of treating the hair.

As illustrated in Fig. 17, the heating element 10 comprises an iron rod or core 30 surrounded by a porous material 32, such as asbestos, and encased within a perforated sleeve 33 of bakelite or the like. The asbestos or other porous material serves to absorb liquid which is vaporized by the heat of the core 30, and the perforations in the tube 33 enable the vapors to readily pass into the hair wound on the said sleeve 33.

The means 15 for transmitting the energy 30 for heating said element 10, shown in Figs. 1 to 3, inclusive, may consist of a solenoid coil or helix 40 through which currents of electricity are adapted to be sent in opposite directions, preferably at high frequency. The solenoid coil 40 may be placed inside or outside of the heat-generating element 10, and may be arranged so as to supply the energy to one or a number of said elements 10. In fact, the solenoid may be made of a size to supply 35 energy to all of the heating elements used upon a head in carrying out the permanent waving, sometimes some forty or more in number, but usually a lesser number, as from twenty to thirty (see Fig. 9).

40 As shown in Figs. 1-8, 11, 12, and 13, the solenoid coil 40 is arranged to surround a single heat-generating element, and a number of such solenoid coils corresponding to the number of heat-generating elements em-

45 ployed, are provided.

The solenoid coil 40 is preferably mounted upon a tough fiber tube 41 which serves as an envelope for enclosing the heat-generating element 10, the strand of hair wound thereon, and the wrapping which is employed in carrying out permanent waving, as illustrated in Fig. 18. The solenoid coil 40 is preferably externally surrounded by a tube 43 of similar material, providing a casing for the 50 said solenoid coil.

55 As shown in Figs. 11 and 12, the heat-generating element 10 is shown as physically incorporated with the solenoid coil 40 and its casing. In Fig. 11 the heat-generating element 10 is formed as a tube 45 surrounded by

a spaced perforated tube 46 of fiber or the like, around which the solenoid coil is wound. The solenoid coil 40 is here exposed to air circulation for reducing its temperature, and the perforations in the tube 46 also serve for circulation of air for carrying off heat which is exteriorly radiated by the said heat-generating element 10.

70 In Fig. 12 the heat-generating element 10 is also in the form of a tube 50, on which the solenoid coil 40 is wound, and the solenoid coil may be covered with a sleeve 52 similar to the sleeve 43, Fig. 3, preferably provided with vents 51 therein.

75 As shown in Figs. 13 and 14, the heat-generating element 10 is combined with the paper tube which is usually placed around a strand of hair prepared for the heat treatment. For example, a sheet of metal 54 (iron preferably) is wound in a sheet of paper 55 to form a tube which is placed over the wound strand of hair in the same manner as the paper tube shown in Fig. 18. An asbestos or other suitable sheet 56 may be placed around the paper tube 55 opposite the metal sheet 54 to retard the outward radiation of heat. In this case, also the solenoid coil 40 may be formed as a simple winding capable of self-support, which is simply placed over the wrappings of the prepared strand of hair, to put it in position for inductively supplying energy to the heat-generating element 10.

80 An oscillating or alternating current may be supplied to or produced in the solenoid coil 40 by any suitable means. As shown in Figs. 1 and 2, and the diagrams Figs. 4 and 5, the solenoid coil is connected by means of leads or wires 58, 59, with a high frequency oscillator conveniently consisting of a condenser 60, a spark gap 62 across which said condenser is adapted to discharge, and in the circuit of which said solenoid coil 40 is placed. An inductive kick coil 64 is placed in one of the leads 66, 67, from an ordinary 85 lighting circuit, and one of the terminals of the spark gap, as the terminal 69, is made displaceable, so as to act as an interrupter for the inductive kick coil, and is placed within the magnetic influence of the kick coil 64, so as to interrupt the circuit when said kick 90 coil 64 is traversed by an electric current. On the break, the kick coil produces discharges across the small gap between the terminals of the spark gap 62, between terminals 69, 69' and this entrains a series of high frequency 95 oscillations to and from the condenser 60, across said spark gap, and through the solenoid coil or helix 40. This action of the kick coil and of the condenser continues as long as 100 electrical connection is made through leads 66, 67, with the lighting circuit, which may be of any voltage commercially used.

105 The combined circuit breaker and discharge terminal 69 is normally pressed against the stationary contact 69', as by 110

spring means indicated by numeral 70, Figs. 1 and 2, though other means may be used. The spring means 70 may conveniently consist of a coil spring 72 on a rod 73 bearing 5 against a sleeve 74 which in turn bears against one of the arms 75 of a lever 76 carrying said terminal 69.

In Figs. 6 and 7 the energy transmitting devices 15 are arranged in circuits 77 without any appreciable capacity, high frequency oscillations in the circuit 77 being produced by means of a transformer 78 the primary of which is in an oscillating circuit 79 of usual form, containing a condenser 60 and 10 a spark gap 62. The energy for charging the condenser 60 may be derived from a lighting circuit (see leads 66, 67) through a transformer 80. The circuits shown in Figs. 6 and 7 are alike, except that in Fig. 6 the condenser and spark gap are in parallel, while 15 in Fig. 7 these parts are in series.

The magnetic variations in the field of the solenoid coil 40 are transmitted through 20 space to the metal of the heat-generating element 10, producing eddy currents therein and molecular friction or hysteresis losses if the element be composed of a magnetic material, and thereby heating said element to 25 produce the heat for the permanent-wave hair treatment.

As shown in Fig. 8, the energy for said heating means may be supplied in the form of electromagnetic waves from an antenna, 30 directional or otherwise, which is preferably arranged as a series of wires 100 curved over the seat of the person whose hair is being waved, as illustrated in Fig. 8. These wires are preferably arranged in the manner of the wires in a directional radio telephone or 35 telegraph sending station, and concentrate the transmitted energy toward the position of the person undergoing hair treatment. The heat-generating element is preferably 40 surrounded by a solenoid coil 40 similar to that shown in Figs. 3, 11, 12, or 13, and in this case the ends of the wire constituting 45 the solenoid are joined to produce a local receiving circuit. The ether disturbances set up through the wireless antenna 100 produce 50 an alternating or oscillatory current in the solenoid 40 which is designed to be in resonance with the wireless transmitter, and this flow of current in the solenoid in turn produces 55 magnetic effects or disturbances which heat the heat-generating element in the field of said solenoid in the manner hereinbefore described.

As shown in Figs. 9 and 10 the energy-transmitting means may comprise a large coil 16 which is in circuit with means for producing an alternating or oscillatory current. The coil 16 transmits energy through 60 space to the various heat-generating elements 10 used for waving a head of hair, by mag-

netic induction as before described. This construction eliminates a large number of lead-wires to individual energy-transmitting coils 16 such as shown in Figs. 1 and 2, but requires considerably more powerful currents in the circuit thereof than is the case where each of the coils 16 is supplied with only the energy for locally producing the heat effect in the individual heat-generating element immediately associated therewith. 70 In the construction shown in Figs. 9 and 10, the coil 16 is in the form of a flat spiral 105, known as a pancake coil, composed of a metal strip 107 with an insulating strip 108 between the metal spirals, and the whole is insulated 75 as by a covering 110 of suitable insulating material.

The pancake coil 105 is adapted to be raised and lowered into position near or surrounding the head of the person whose hair is being waved, and is thus brought in proximity to the heat-generating elements 10, the energy of the pancake coil being transmitted directly to said elements 10 associated with the individual prepared strands of hair. 80

Instead of the transformer and spark gap arrangement hereinbefore set forth, any other known means may be employed for producing high frequency oscillations for energizing the heater elements. 85

The invention may receive a great variety of embodiments, and is not limited to the specific embodiments herein illustrated and described.

It is characteristic of this invention that the heat generated is concentrated in the heat-generating element which is closely associated with the hair to be curled or waved, so that the heating effect is utilized internally to produce its intended effect upon the hair, and is not dissipated externally to any readily appreciable extent. It is thus differentiated from the permanent wave appliances heretofore in universal use in which the heating element is a resistance coil in a metallic casing which is placed around the prepared strand of hair, so as to enclose the hair and its surrounding layer of absorbent material saturated with a solution of borax or the like, and also usually a paper envelope enclosing such absorbent layer, so that the heat generated in said coil is radiated both inwardly and outwardly, with the result that the casing becomes excessively hot, so that the attendant cannot safely handle it, and the person under treatment is subjected to the cumulative heat effect of the numerous heaters simultaneously in action, whereby her scalp and head are uncomfortably and often distressingly and dangerously heated, and sometimes seriously burned. The solenoid coils which the present invention substitutes for such heaters are not heat-generators, being of ample conductivity for transmitting the electrical energy, without heating, but are mere- 100

ly excitors for the internal heat-generating elements, and their casings (if casings are used) are cool and can be handled with perfect comfort and safety. The internally-generated heat is applied almost solely to the hair and the impregnated absorbent surrounding the hair, and is not expended in heating an enclosing casing, nor is it communicated in any sensible degree to the scalp, so that the person under treatment is nearly unconscious of any heating effect around her head. Thus the process of permanent waving is rendered safe and comfortable, and also is conducted much more quickly because of the internal concentration of the heat.

What I claim is:

1. A hair waving device comprising a heat generating element adapted to be placed in proximity to the hair to be treated, a source of oscillating current, means for inductively transmitting electric energy for heating said element, said transmitting means being energized by said oscillating current at a materially higher frequency than that of commercial alternating current supply systems.

2. A device according to claim 1 in which the energy from said transmitting means is in the form of radio waves.

3. A hair waving device comprising a heat generating element adapted to be placed in proximity to the hair to be treated and means for inductively transmitting energy for heating said element, said transmitting means comprising a resonant circuit carrying a high frequency electric current, and a coil energized thereby, the said heat-generating element being disposed within the field of said coil.

4. A device according to claim 3 in which the heat generating element comprising a body of metal in which eddy currents are induced by the high frequency variation in the magnetic field of said coil.

5. A device according to claim 3 in which the heat generating element comprises a tubular body of magnetic metal in which heat is generated both by eddy currents and hysteresis losses.

6. A device according to claim 1, in which the transmitting means further comprises a solenoid in the magnetic field of which said heat generating element is adapted to be placed.

7. A device according to claim 1, further including a liquid carrier, said heat-generating element being adapted to vaporize the liquid in said carrier to treat the hair to be waved.

8. A device according to claim 1, further including a liquid carrier, said heat-generating element being adapted to vaporize the liquid in said carrier to treat the hair to be waved, and comprising metal electrically insulated from said energy-transmitting means.

9. A hair waving device comprising a metallic heat-generating element, an envelope within which a prepared strand of hair is at least partially enclosed, a coil surrounding said element and adapted to inductively heat the latter, the said coil being energized by an oscillating current of an intensity and frequency such as will inductively generate heat in the said element at a higher rate than the rate of heating of the coil due to the inherent resistance of said coil.

10. A device according to claim 3, further including means supplying a high frequency current to said coil of such character as not to heat said coil to a degree which will be uncomfortable in immediate proximity to the head.

11. A device according to claim 1, in which said heat-generating element comprises a metal piece extending lengthwise of the strand of hair to be treated.

12. A device according to claim 1, in which said heat-generating element comprises a metal piece on which hair is placed or wound.

13. A device according to claim 1, further including a liquid carrier, adapted to surround hair to be waved, said heat-generating element being arranged inwards of the outside of said liquid carrier, whereby the heat does not require to pass entirely through said liquid carrier to reach the hair.

14. A device according to claim 1, further including an outside wrapper adapted to surround hair to be waved, and a liquid carrier, said heat-generating element being arranged inwards of the outside of said wrapper, whereby the heat does not require to pass through said wrapper to reach the hair.

15. A method of waving hair, comprising enclosing a heat-generating means and a moisture carrier in an enclosure surrounding a prepared strand of hair, and producing heat in said element by electromagnetic induction to cause the latter to vaporize the moisture in said moisture carrier.

16. A method of waving hair according to claim 15, in which the heat is produced in said element by high frequency electro-magnetic induction.

17. A method of hair waving consisting in enclosing a prepared strand of hair, a heat-generating element of metal, and a moisture carrier within a solenoid coil, and directing high frequency electric oscillations through said coil to heat said element by magnetic induction.

18. A method of waving hair which comprises arranging a prepared strand of hair in close proximity to electro-conductive material and heating said material by subjecting it to a high frequency variable electro-magnetic field, the positioning of the hair with respect to the said material being such that heat thus generated will pass from the said material to the hair.

19. A method of waving hair which comprises arranging a prepared strand of hair and a moisture carrier in close proximity to an electro-conductive element and heating said element by subjecting it to a high frequency variable electromagnetic field, the positioning of the hair and moisture carrier being such that the heat thus generated will vaporize the moisture, the vapor of which will permeate the hair.

10 In witness whereof, I have hereunto signed my name.

BENNO FREDERICK JANCKE.
